(57) **CLAIM**

The ornamental design for a recreational shoe spike, as shown and described.

DESCRIPTION

FIG. 1 is a front perspective view of a recreational shoe spike showing our new design;

FIG. 2 is a rear perspective view thereof;

FIG. 3 is a bottom view thereof;

FIG. 4 is a side view thereof;

FIG. 5 is an opposite side view thereof;

FIG. 6 is a front view thereof;

FIG. 7 is a rear view thereof;

FIG. 8 is a top view thereof; and,

FIG. 9 is a perspective view thereof, shown in a used condition with a shoe shown in broken lines.

The broken lines of cross shoe and threads in the views form no part of the claimed design.

1 Claim, 5 Drawing Sheets
